T. HALL.
TYPOGRAPHIC MACHINE.

No. 65,807.

Patented June 18, 1867.

UNITED STATES PATENT OFFICE.

THOMAS HALL, OF BERGEN, NEW JERSEY.

IMPROVEMENT IN TYPOGRAPHIC MACHINES.

Specification forming part of Letters Patent No. 65,807, dated June 18, 1867.

To all whom it may concern:

Be it known that I, THOMAS HALL, of Bergen, Hudson county, State of New Jersey, have invented a new and useful Machine for Writing with Type or Printing on Paper or other substance; and I do hereby declare that the following is a full, clear, and exact description of the construction and operation of the same, reference being had to the annexed drawings making a part of this specification, in which—

Figure 1 is a perspective view of the machine, showing its working parts. Figs. 2 and 3 are side and front elevations of the table and connections; and Fig. 4, an end view of stop-motion, as described in following explanation.

A A represent the frame of the machine, to which all the working parts are attached. B B is a plate extending from side to side of the frame, to which are fixed the type and connections for operating them. C C are hangers or supports for type-levers E e E e, which are acted upon by levers D D through rods g g. The type F F are fixed on levers e e, so that they can be rotated on their round shanks to adjust them so that they will strike parallel with each other. R is a ring or circular stop or cushion, provided to stop the type-lever from descending too far, or sinking into material being printed on. This ring is adjustable by rods V V and nuts on plate B. The type-levers e e are also adjustable by set-screw e'. (Shown in Fig. 2.) The levers D D, which operate the type, are provided with finger-pieces d d, which project through the case and form a key-board, by which the machine is operated upon. 2 is a hollow shaft, adjusted with a slot, so that the pieces 1 1, which are attached to levers D D, can enter the slot, any one of which entering tip the shaft 2, so that no other can enter until the first is withdrawn, as shown in views, Figs. 1 and 4. H is a rock-shaft, which is operated by levers I I and rods i i, rods i i being acted upon by levers D D. The motion of shaft H is communicated, through lever J, rod j, lever L, lever L', and rod M, to frame N N, which slides from side to side on rails O O, carrying table P. (Shown in Figs. 2 and 3.) Hinged to frame N is a clutch, n, (shown in Figs. 2 and 3,) through which rod M

slides freely from left to right, but which bites on rod M when it moves from right to left, and carries the frame N with it.

The movement of the frame N takes place as the action of each type and the distance moved corresponds with the width of the type used.

The adjustment is made either by the various lengths of levers I I I I, or by the rods i i being made of different lengths, so that levers D D D D shall cause rods i i to move but a part of the movement of levers D D D D.

K is a nut on the lever J, by turning which will cause lever J to be lengthened or shortened, thereby giving facility for varying the space between each letter printed uniformly. Q is a lever, connecting shaft t, lever s', rod r, lever q, and rod p to bar X, (shown in Figs. 2 and 3,) the object of which is to move the frame N, carrying table P, to the right or left. When moved to the right it acts on clutch n and raises it, enabling it to slide freely on rod M. The table P is placed on frame N, and slides freely backward and forward by the action of rail T, to which it is attached by clasp U. Rail T is fixed at each end to rods T' T', on which it slides, and is moved parallel by rods v v and levers W W on shaft Y. Shaft Y is moved by rod y, connecting with knob Z, by which the operator can move table to any position, and retain it there by a catch at lower end of knob Z, which catches into notches in plate z. V is a plate, which moves parallel with lower edge of plate z, in order to release knob Z from notch in z, and is operated by levers a a, connected together, and rod b, lever c, hollow shaft c', and catch f. Spring S holds catch f in place until frame N moves up to it and pushes, by rod m, the spring S from catch f, and thereby allowing spring on c' to operate on lever c and push rod b, the end of which, b', coming in contact with lever 3 on hollow shaft 2, turns it, so that none of the pieces 1 1 1 can pass down, and thus stopping the action of the type until frame N is moved, thereby lifting catch f, and allowing spring S to hold it in place, when catch f is released and stops the action of type-levers. It also pulls down parallel bar V and releases catch from notch in plate z, to enable it to move up a line or more, which can

be done either by hand on knob Z, or by a lever or slide, when table is moved back by lever Q.

G is a counter-weight on type-lever E, to return it to its upright position, and is so arranged that it acts with greater power when the type is up than when it is in contact with the substance to be printed, in order that a greater force be required at the commencement of its movement than at any other point to move it. 4 is a light spring on shaft 2, to return it after being tipped by b'. h is a spring to react against pressure on levers I on shaft H to feed-table for each depression of a key. d' is a key merely to move the table, in order to have blank space where required between words, &c., when printing.

To use the machine, paper or other material is placed on table P, and held by catches. (Not shown in drawings.) A ribbon, saturated with ink, is stretched over it, by any convenient arrangement, so that the type will strike the impression through the ribbon onto the paper. The table is placed onto frame N, with the catch U on the rail T, and is moved by knob Z and lever Q to any position desired. The keys d d' are depressed in the order that will spell words; and key d' will give a blank space by merely moving the table one space to the left for each depression. The other keys, which connect with type, will cause each type to drop onto the paper at the same place in the machine, the paper moving at each impression the distance required for the letter used by means of the various lengths of levers on shaft H. The stop-motion makes the lever which is touched first stop all the others from operating while it is depressed.

The lever Q shows at all times the position of the table on the machine, and gives facility for placing it anywhere from side to side.

Two or more copies can be taken at one time by laying impression-paper or inked ribbon or silk between layers of paper, so that the type will strike the impression through all.

I claim as my invention and desire to secure by Letters Patent—

1. Weights attached to the type-levers, when they are so arranged that they act with less power when the type is making its impression than at any other position.
2. The stop-mechanism 1 1 1 1 and hollow shaft 2, substantially as described.
3. The arrangement for moving table by varying length of levers to suit each type, substantially as described.
4. The method of spacing between letters and words by a variable length of lever J, by which the space for each letter is increased or diminished equally, substantially as shown.
5. Moving paper by the clutch n on straight rod M, substantially as described.
6. Lever Q and connections, for moving table, substantially as described.
7. Parallel motion, for moving table backward and forward, substantially as described.
8. Ring B or its equivalent, for stopping type when making an impression.
9. Automatic stop, operating when the printing has reached the end of the lines, substantially as described.
10. Varying the length of movement of the table P, or substance to be printed upon, by causing the keys to move different distances before acting on the feed mechanism.

THOS. HALL.
